UNITED STATES PATENT OFFICE

168,707

SUN VISOR MIRROR UNIT

Abraham Pavenick, New York, N. Y.

Application August 22, 1951, Serial No. 16,404

Term of patent 7 years

(Cl. D14—6)

To all whom it may concern:

Be it known that I, Abraham Pavenick, a citizen of the United States, residing at New York city, in the county of New York and State of New York, have invented a new, original, and ornamental Design for a Sun Visor Mirror Unit, of which the following is a specification, reference being had to the accompanying drawing, forming part thereof.

In the drawing:

Fig. 1 is a front elevational view of a sun visor mirror unit showing my new design;

Fig. 2 is a top plan view of the same;

Fig. 3 is a side elevational view taken from the right hand side of Fig. 1;

Fig. 4 is a rear elevational view; and

Fig. 5 is a perspective view.

I claim:

The ornamental design for a sun visor mirror unit, substantially as shown.

ABRAHAM PAVENICK.
